Filed Sept. 6, 1967, Ser. No. 8,685

Term of patent 14 years

Int. Cl. D23—02

U.S. Cl. D23—71

FIG. 1.

FIG. 2.

FIG. 3.

FIG. 4.

FIG. 5.

FIG. 1 is a perspective view of a cover for a toilet bowl or the like, showing my new design in its normal position;

FIG. 2 is another perspective view thereof showing the lid in a raised position;

FIG. 3 is a top plan view thereof with the sides extended;

FIG. 4 is a bottom plan view thereof; and

FIG. 5 is a perspective view of a modified form of the cover for a toilet bowl or the like shown in FIG. 1 wherein said modification resides in the elastic securing bands.

The broken line representation of a toilet in FIGS. 2 and 5 are for purposes of illustration only.

I claim:

The ornamental design for cover for a toilet bowl or the like as shown and described.
